UNITED STATES PATENT OFFICE

2,500,490

LAUNDRY TUB

Anthony D. Grenga, Youngstown, Ohio

Application November 29, 1945, Serial No. 631,564

4 Claims. (Cl. 220—23.4)

1

This invention relates to tubs and more particularly to twin tub assemblies commonly used in home laundering.

The principal object of the invention is the provision of a portable laundry tub assembly.

A further object of the invention is the provision of a portable laundry tub assembly and means for holding the tub portions in a frame portion of the assembly.

A still further object of the invention is the provision of a laundry tub assembly incorporating a center mounting means for the tubs.

A still further object of the invention is the provision of means for mounting porcelain enameled laundry tubs in a portable frame, the mounting means incorporating resilient construction engaging the tubs centrally thereof.

The portable laundry tubs shown and described herein have been devised to form convenient portable and practical laundry tubs which may be used for home laundering operations either with or without a washing machine. The tubs may be employed as wash tubs or as rinse tubs and are so formed that the assembly is resilient to a degree enabling the tubs to be easily rolled about and at the same time protecting the porcelain tubs themselves from damage.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the laundry tubs with parts broken away and parts in cross section.

Figure 2 is a cross sectional end elevation of the laundry tubs.

Figure 3 is a top plan view of the laundry tubs, section line 2—2 on Figure 3 indicating the cross section illustrated in Figure 2.

By referring to the drawings and Figure 1 in particular, it will be seen that the laundry tub assembly consists of a pair of tubs 10 and 11 positioned side by side in a frame which is formed of two circular sections 12 and 13 which are held together by means of spacing members 14. The tubs 10 and 11 are separated by means of a tubular resilient member 15 which is held between the tubs 10 and 11 by means of a bolt 16 passed therethrough, the bolt 16 engaging oppositely dis-

posed openings in the side walls of the tubs 10 and 11.

The frame, which is essentially formed from the circular sections 12 and 13, is elevated with relation to a floor or other supporting surface by means of four legs 17, two of which are attached to each of the circular sections 12 and 13. By referring to Figures 2 and 3 of the drawings, it will be seen that the legs 17 are so spaced with relation to the circular sections 12 and 13 that together they form four widely spaced, properly positioned supports for the frame and tub assembly. The legs 17 are preferably formed of strip stock material of channeled construction and are preferably riveted to the circular sections 12 and 13 as by rivets 18.

In order that the tubs 10 and 11 may be held in proper relation in the circular sections 12 and 13, mounting means is provided centrally of each tub and consists of a circular disc 19 provided with a centrally located opening 20 through which a bolt 21 is positioned. A gasket 22 is positioned immediately beneath the disc 19 and on the upper surface of the bottom of the tub and a similar construction consisting of a gasket 23 and a secondary disc 24 are positioned immediately below the bottom of the tub and the bolt 21 extends therethrough. A semi-U shaped bracket 25 with an opening formed in each of the arms thereof serves as a means of connecting the bolt 21 and the double discs and gasket assembly with a pair of angularly positioned braces 26 and with a transversely positioned cross member 27. The bolt 21 and the double disc and gasket assembly are affixed to one of the arms of the semi-U shaped bracket 25 and the angularly positioned leg braces and transversely positioned cross member 27 are affixed to the other arm of the semi-U shaped bracket 25 as by means of a bolt and nut 28. This construction effectively unites the tubs 10 and 11 with the sections 12 and 13 and the legs 17 by way of the transversely positioned cross member 27 and the angularly positioned leg braces 26.

It will be observed that the formation of the semi-U shaped bracket 25 provides for the resilient tensioning of the tub 10 or 11 therethrough so that they can be firmly yet yieldably held in position in the circular sections 12 or 13. It will be obvious that the tubs are preferably formed with annular flanges 10A and 11A which rest against the uppermost edge of the circular sections 12 and 13 and thereby position the tubs effectively in the frame. Caster wheels 29 are provided on the lowermost ends of each of the legs 17 and the whole assembly forms a uniquely

portable twin laundry tub assembly which may be advantageously used by a housewife in laundering.

Having thus described my invention, what I claim is:

1. In a portable laundry tub assembly a pair of circular frame sections and means connecting the said frame sections together, a pair of tubs, one positioned in each of the said circular frame sections, legs for holding the said frames in elevated relation to a supporting surface, each tub having a centrally located opening in the bottom thereof, and means for yieldingly holding the said tubs in the said frames, said means including an element engaging the centrally located opening in the bottom of each of the said tubs and depending therefrom, a U-shaped resilient member attached at one of its ends to the said element, and brace elements positioned between the other end of the said U-shaped member and the said legs.

2. In a portable laundry tub assembly a pair of circular frame sections and means connecting the same together, a pair of tubs having centrally disposed openings in the bottom thereof, said tubs positioned one in each of said circular frame sections, legs for holding the said circular frame sections in elevated relation to a supporting surface, and means for yieldingly holding the said tubs in the said frames, said means including a bolt and washer engaging the centrally located openings in the bottom of each of the said tubs and depending therefrom, a spring member attached at one end to the said depending bolt beneath the bottom of the said tubs and brace members connected to the other end of the said spring member and to the said legs.

3. In a laundry tub assembly including a supporting frame and a pair of tubs positioned adjacent to one another and having openings in their bottoms, means for yieldingly holding the tubs in the said frame, said means including bolt and washer assemblies in the said openings, U-shaped spring members each having one end thereof affixed to one of the said bolt and washer assemblies beneath the bottoms of the said tubs and stress members connecting the other ends of said U-shaped spring members with the said supporting frame.

4. In a portable laundry tub assembly including at least one tub and a supporting frame therefor, means for yieldingly holding the said tub in the said frame, said means including a bolt and washer assembly engaging the said tub and stress members connected with the said supporting frame, a curved section of resilient metal secured to said bolt and beneath said tub, said stress members connected with the said curved section of resilient metal.

ANTHONY D. GRENGA.
